UNITED STATES PATENT OFFICE.

CORNELIUS G. HASTINGS, OF GLENDALE, CALIFORNIA, ASSIGNOR TO HASTINGS
TUNNEL SYSTEM COMPANY, A CORPORATION OF NEW YORK.

ERECTING-MACHINE.

1,342,503.

Specification of Letters Patent.

Patented June 8, 1920.

Application filed November 26, 1915. Serial No. 63,495.

To all whom it may concern:

Be it known that I, CORNELIUS G. HASTINGS, a citizen of the United States, and a resident of the city of Glendale, in the county of Los Angeles and State of California, have invented certain new and useful Improvements in Erecting-Machines; and I do hereby declare that the following is a full, clear, and exact description of the same, reference being had to the accompanying drawings, and to the numerals of reference marked thereon, which form a part of this specification.

This invention relates to a machine adapted for use particularly in the construction of tunnels, conduits, and the like, although of course well adapted for other similar purposes, and more particularly adapted for use with tunneling shields such as set forth in my co-pending application for "tunneling shields", filed November 19th, 1914, Serial No. 872,921. By this invention rapid construction of a tunnel or conduit is assured, inasmuch as the building blocks may be laid in built up relation with the utmost facility and may be held temporarily in position by the machine until the interlocking means provided for the purpose are fitted with the building blocks to hold the same properly disposed until the grouting or surrounding layers of concrete are blown therearound.

It is an object therefore of this invention to construct an erecting machine with a movable platform or carriage provided with suitable power mechanism for operating an extensible arm and swinging the same in any radial direction to lay a row of blocks in built up relation in a circumferential line irrespective of the particular contour of the tunnel or bore under construction.

It is also an object of this invention to construct an erecting machine for use in building up the lining of a tunnel or conduit from the interior thereof, the machine acting to grip and elevate the blocks to any desired position.

It is also an object of this invention to construct a machine for placing the building blocks comprising the lining of a tunnel in built up relation, said machine movable upon a carriage or platform advanced from time to time as successive rows or layers of blocks are laid in position, upon

bracket frames having rollers thereon and connected releasably to the reinforcing means for each row of blocks on the interior of the tunnel or conduit.

It is furthermore an object of this invention to construct an erecting machine comprising a traveling platform with a pivotally mounted telescoping extensible carrying arm mounted thereon and provided with jaws adapted to grip and pick up a block to be swung by said arm to the desired position and projected thereinto so that a series of said blocks may be laid one upon another to form a complete row or additional layer in the tunnel lining.

It is also an object of this invention to construct an erecting machine adapted to travel within a tunnel or conduit, following closely upon a tunneling shield to lay a row of blocks in built up relation within the flexible apron at the rear end of the shield prior to the successive advancements thereof.

The invention (in a preferred form) is illustrated in the drawings and hereinafter more fully described.

In the drawings:

Figure 1 is a diagrammatic view of a tunnel under course of construction, illustrating an erecting machine embodying the principles of my invention mounted therein.

Fig. 2 is a horizontal section taken through the forward end of the tunnel under construction, illustrating a plan view of the shield and erecting machine within the tunnel.

Fig. 3 is a fragmentary detail section partly broken away, taken on line 3—3 of Fig. 1.

Fig. 4 is an enlarged plan view of one of the locking clamps for the movable platform or carriage.

Fig. 5 is a side view thereof, illustrating the same connecting the carriage to a reinforcing T-member laid in the walls of the tunnel.

Fig. 6 is a fragmentary detail section taken on line 6—6 of Fig. 1.

Fig. 7 is a fragmentary detail section with parts omitted taken on line 7—7 of Fig. 1.

Fig. 8 is a fragmentary side elevation with parts in section of the telescoping extensible arm of the erecting machine.

Fig. 9 is a sectional detail of the inner end of said arm, with parts broken away.

Fig. 10 is a detail section taken on line 10—10 of Fig. 8, with parts shown in elevation.

Fig. 11 is a fragmentary vertical section taken on line 11—11 of Fig. 10.

Fig. 12 is a detail view partly in section and partly in elevation, illustrating the end of the telescoping arm in gripping relation with a block.

10 Fig. 13 is a section taken on line 13—13 of Fig. 12.

As shown in the drawings:

The reference numeral 1, indicates the earth through which the tunnel bore is projected by means of a tunnel shield indicated as a whole by the reference numeral 2, and receiving laid in built up relation therein a series of rows of interlocking building blocks 3, all substantially the same shape and size, although a few thereof may vary a slight amount in configuration to permit construction of a tunnel of oval or elliptical shape, such as shown in Fig. 1. Each of said blocks 3, is provided with a narrow slot or groove running from end to end on the inner surface thereof, and at its middle portion with an enlarged recess within which is mounted a small channel 4, and when said blocks are laid in built-up relation, reinforcing and retaining means consisting of a plurality of T-bar sections 5, are connected and placed with the webs thereof extending into the longitudinal grooves in said blocks, as clearly shown in Figs. 2, 3, 35 and 6. Adapted to be connected to the built up T-bar ring 5, at each side of the bore are angled brackets or frame members 6, each thereof, as clearly shown in Figs. 3, 6, and 7, consisting of a pair of angle bars secured 40 one to another in any suitable manner. Attaching clamps or brackets are provided at the extremities of the legs of each of the bracket frame members 6, a detail of one of which is shown in Fig. 6, the same consisting of a clamping plate 7, riveted to the web of the frame members 6, and another clamping member 8, adjustably connected to said web member 7, by means of a threaded bolt 9, provided with a thumb nut 10, which, 45 when threaded inwardly on the bolt, clamps the member 8, together with said member 7, on the flanges of the T-bar ring 5.

Secured upon each of the angled frame members 6, is a bracket 11, in which is journaled a roller 12, and a platform or carriage consisting of I-beams 13, suitably connected to one another in any suitable manner, having a floor 14, laid thereon, and with angled track members 15, on the under surface thereof, is constructed to roll upon said rollers 12. Means are also provided upon the moving platform or carriage to lock or retain the same in a fixed position within the tunnel from time to time, and for this purpose a hinged plate 16, is riveted to each

end of the front and rear I-beams 13, and pivotally connected thereto is a bracket plate 17, and threaded through one side of the end of said bracket plate 17, is a clamping bolt 18, having a swiveled V-shaped head 19, to grip against the edge of the flange of the T-bar ring 5. A detachable wrench handle 20, is provided, adapted to be engaged over the squared end of the bolt 18, for the purpose of tightening or loosening the same, as desired, upon the T-bar ring 5, and formed at the rear end of the pivoted or hinged clamping plate 17, is a tail piece 21, adapted to limit the outward swing of said clamping plate to a horizontal position.

Mounted in any convenient position upon the carriage or platform is a compressed air reservoir 22, and connected thereto by means of a pipe 23, is a compressed air engine 24, connected on one side of the crank shaft of which is a niggerhead 25, and on the other side thereof a worm 26. Mounted in suitable bearings provided for the purpose parallel to the engine 24, is a long tubular shaft 27, provided with a worm wheel 28, meshing with the worm 26, and leading into the end of said tubular shaft 27, is an air supply pipe 29, connected to the reservoir 22.

Secured upon the forward end of the tubular shaft 27, the detail of connection of which is shown in Fig. 8, by means of a bracket 29^a, is a long telescoping arm consisting of a tubular section 30, having fitted therein another tubular section 31, which in turn has fitted therein another tubular section 32. Communicating laterally through the end of the tubular shaft 27, is a pipe 33, which is connected through a four way valve 34, having a relief opening therein, to branch pipes 35 and 36, respectively, one leading into one end of the tubular member 30, and the other leading into the middle portion thereof near a partition 37, therein. 100 Mounted within the tubular member 30, between the end thereof and the partition 37, is a piston 38, having a piston rod 39, connected thereto extending slidably and sealingly through said partition 37, and at its 110 end threaded into the end of the tubular member 31, so that movement of the piston acts to extend or retract the tubular member 31, from or into the tubular member 30. Also connected into said tubular shaft 27, 120 is a flexible pipe 40, which communicates through a four way valve 41, having a relief opening therein, and branch pipes 42 and 43, respectively, said pipes each connected through the walls of the tubular member 31, the pipe 42, communicating with a long passage 44, afforded between the walls of said tubular member 31, and a cylindrical sleeve 45 therewithin, and the other pipe 43, directed through said tubular 125 130

member 31, and through said sleeve at the forward ends thereof. A partition 46, is provided within the tubular element 31, at the end of the sleeve 45, and mounted 5 within said tubular element within the sleeve 45, is a piston 47, having a piston rod 48, secured thereto which extends sealingly through the partition 46, and is secured in the head at the inner end of the tubular 10 member 32. A head or closure 49, is provided in the end of the tubular member 32, and has a narrowed extension 50, through which extends a small shaft 51, having squared ends to receive attached thereto a 15 long lever or wrench. Secured upon said shaft 51, on each side of the narrowed extension 50, are eccentrics 52, and pivoted at each side at the outer end of said extension 50, are jaws 53, the gripping or contact 20 surfaces of which are roughened or serrated. Connected between each of said jaws 53, are a pair of toggle links 54, and connected to the common pivot thereof are connecting rods 55, which are connected to the respective 25 eccentrics 52.

The operation is as follows:

The telescoping arm 30—31—32, is capable of rotating with the tubular shaft 27, as a center, through 360°, and by proper manipulation of the controlling valves 34 and 41, said tubular arm may be extended radially to any desired length for the purpose of positioning a block in place. Said tubular arm may engage with a block in the inlaid 35 channel 4, thereof, when said block is at any point within reach of the arm, though usually below the same and the valves 34 and 41, are then actuated to extend the arm carrying the block to place the block in position, after which an operator inserts the 40 interlocking rods, such as disclosed and described in my co-pending application for "tunnel block and tunnel construction", filed October 18th, 1915, Serial No. 56,517.

The operation of extending the elements 45 31, from the element 30, is effected by adjustment of the valve 34, such that air under pressure is admitted through the branch pipe 35, behind the piston 38, thereby forcing the same along in its tubular cylinder 30, with the fluid in front of the piston expelled through the member 36, and through the outlet relief pipe of the valve 34. If this extension of the tubular arm is insufficient, the tubular element 32, may be extended from the extended element 31, by adjusting the valve 41, such that air is admitted through the passage 44, behind the piston 47, thereby driving the same forwardly in the cylinder and the fluid in front of the piston is expelled through the pipe 43, and outwardly through the relief pipe in the four way valve 41. The retractive or telescoping movements of the parts of the 55 60 65 extensible arm are effected by so adjusting

the valves 34 and 41, that the air under pressure is admitted in front of the respective pistons 47 and 38, and the fluid within the respective cylinders at the rear of the pistons, as said pistons move inwardly therein, 70 is expelled through the piping connections and outwardly through the relief or outlet pipes of said respective valves 41 and 34.

Of course the telescoping arm may be rotated any desired degree by operation of the 75 compressed air engine 24, and the nigger-head 25, also operated thereby, may be utilized, by winding a cable therearound, to haul the carriage of the erecting machine forwardly or rearwardly within the tunnel, 80 as desired. However, when the carriage has been moved to a desired point within the tunnel, the clamping plates 17, are swung downwardly to engage the T-bar rings 5, and the adjusting bolts 18, are then actuated 85 by the cranks 20, provided for the purpose, to tighten the clamps upon the T-bar rings and thus hold the carriage substantially in a fixed position. As the tunnel work progresses, additional brackets or frames 6, are 90 placed in position by clamping the same upon the sectional T-bars 5, thus providing a support with rollers thereon on which the carriage may be moved from time to time as the work requires. As already pointed 95 out, the layer of blocks built up within the tunnel by the telescoping arms, is that layer at the end and within the apron of the tunnel shield 2, and with the parts shown in the position illustrated in Fig. 2, the carriage and associated mechanisms are ready to be advanced forwardly in the tunnel, but the rows of blocks immediately behind the apron of the tunnel have been omitted for 100 clearness.

I am aware that various details of construction may be varied through a wide range without departing from the principles of this invention, and I therefore do not purpose limiting the patent granted 110 otherwise than necessitated by the prior art.

I claim as my invention:

1. A tunneling machine comprising a movable carriage, a telescoping arm comprising interfitting sections rotatably mounted on 115 said carriage, jaws mounted on the outer section and mechanism for independently or collectively extending and retracting said sections.

2. In a machine of the class described, 120 bracket frames adapted to be connected to the interior of a tunnel, rollers on said bracket frames, a carriage adapted to move on said rollers, a telescoping arm adjustably mounted on said carriage, means actuating 125 said arm, pivotally mounted gripping jaws secured to the outer end of said arm and an eccentrically operated mechanism for adjusting said jaws to engage a block.

3. In a machine of the class described, a 130

movable carriage, a telescoping arm thereon comprising independently or collectively adjustable sections, an air reservoir, independent connections between the same and each section whereby the sections may be independently or collectively manipulated, an engine for adjusting said arm to different angular positions, and means on said arm for engagement with a block to move the block into position by said arm.

4. In an erecting machine of the class described, a rotatable arm comprising a plurality of telescoping sections, power means adapted to be applied independently to different sections for extending and retracting said sections, and clamping means on said arm for engagement with the building blocks to be moved by said arm into built up positions.

20 5. In a device of the class described, a movable carriage, means anchoring said carriage at different points; mechanism for swinging said arm to different radial positions, said arm comprising a plurality of 25 telescoping sections, power mechanisms for independently and collectively extending and retracting said sections, and toggle gripping means on said arm for engagement with a block to move the same into any desired position by said arm.

6. A tunnel lining machine comprising a carriage, a rotatable adjustable arm secured thereto, a power operated mechanism for rotating said arm in a vertical plane, power

operated independently acting means for 35 varying the adjustment of said arm, jaws secured to the arm for engaging a lining block, and toggle arms connecting said jaws and arm.

7. A tunnel lining machine comprising 40 track members shaped to be supported by the tunnel wall, tracks thereon, a carriage movable on said tracks, means for securing the carriage in the proper position, a revolute and extensible block carrying member 45 carried on said carriage, mechanism for revolving said member, and mechanisms adapted to coact or act separately for extending said member.

8. In an erecting machine for tunnels, the 50 combination of a carriage adapted to be advanced in the tunnel, an extensible arm pivotally supported on the carriage to swing transversely of the tunnel, and jaws at the outer end of the arm operable to grip and 55 hold a block so as to be set in place by means of said arm, said arm comprising a plurality of pressure chambers each of which is adapted to independently operate a telescopic section of the arm.

60 In testimony whereof I have hereunto subscribed my name in the presence of two subscribing witnesses.

CORNELIUS G. HASTINGS.
